UNITED STATES PATENT OFFICE.

JAMES C. STEEN, OF CINCINNATI, AND PERRIN G. MARCH, OF FERNBANK, OHIO, ASSIGNORS TO THE CINCINNATI SHAPER COMPANY, OF CINCINNATI, OHIO.

SHAPING-MACHINE.

SPECIFICATION forming part of Letters Patent No. 654,857, dated July 31, 1900.

Application filed February 7, 1900. Serial No. 4,834. (No model.)

To all whom it may concern:

Be it known that we, JAMES C. STEEN, residing at Cincinnati, and PERRIN G. MARCH, residing at Fernbank, in the county of Hamilton and State of Ohio, citizens of the United States, have invented certain new and useful Improvements in Shaping-Machines, of which the following is a full, clear, and exact description, reference being had to the accompanying drawings, which form a part of this specification.

Our invention relates to improvements in shaping-machines, and is designed to reduce the friction in the operation of the ram; to furnish a means by which the feed may be regulated at will without stopping the machine; to provide a means for varying the gear of the machine, so as to regulate the velocity of the ram's travel, and to provide a simple means for supporting the table with a minimum of friction. The character of these improvements will appear more fully as we proceed with the description.

In the drawings, Figure 1 is a side elevation of a shaping-machine to which our improvements have been applied. Fig. 2 is a rear view looking at Fig. 1 from the right, several parts being shown in section. Fig. 3 is a detail in section of the mechanism for controlling the feed. Fig. 4 is a section through Fig. 3 on the line 4-4. Fig. 5 is a detail view showing the mechanism for varying the gear. Fig. 6 is a detail for the support for the table.

Referring to the drawings, A is the usual column or frame supporting the ram B, which carries the tool m at its forward end. The block d is mounted on the screw P, which is carried by the ram B. The block d is provided with a stud f, which passes through the slot o' and has at its upper end the clamping-lever e for clamping the block in any position in the slot o', so that the position of the tool m may be moved forward or backward without changing the length of the stroke of the ram. This is the usual manner of mounting the block d, so that it need not be described further. A pin c is secured in the lower part of the block d and is made longer than the width of the block, so that it sticks out at both sides. Rollers b are loosely mounted on each end of this pin c. Instead of the pin c

the block d may be provided with lugs upon which to mount the rollers b.

The rocking arm C for operating the ram is pivoted in the usual manner in the column 55 A at S and is provided at its upper end with the prongs E, which pass on each side of the block d. These prongs E are slotted, so as to receive the rollers b between the bearing-faces a. We prefer to have this slot open at 60 the top; but of course it may be closed without departing from the spirit of our invention. As the arm C rocks forward and back its motion is communicated to the ram through the rollers b, pin c, and block d, the rollers b 65 running up and down the bearing-surfaces a and turning on the pin c, thus giving the effect of a ball-bearing.

Another improvement is a mechanism for changing the amount or direction of the feed 70 or movement of the table-saddle along the cross-rail while the machine is in motion.

F is the cross-rail, D the saddle, and E the table for carrying the piece to be shaped. The cross-rail F carries the feed-screw g. (See 75 Figs. 1, 3, and 4.) Loosely mounted on the feed-screw g is a rocker i, carrying a reversible pawl j. Said rocker i is operated in any convenient manner, in this case by means of the connecting-rod Q and eccentric R, said 80 eccentric R being geared in the usual manner to the main driving-wheel G. A ratchet-wheel h is keyed to the feed-screw g and is provided with a flange h', upon which is mounted loosely the circular ring k, which 85 has an upwardly and outwardly projecting sleeve k', designed to cover the teeth of the ratchet h. This sleeve k', however, only extends part way around the ratchet h, a portion of it being cut away, so as to leave a 90 number of teeth of the ratchet uncovered, this number being determined by the angle through which the rocker i operates. (See Fig. 4.) The pawl j is of such a shape that when in engagement with the teeth of the 95 ratchet it will turn the ratchet if moved in one direction, but will simply ride over said teeth if moved in the opposite direction. The pawl j is mounted on a stud j', having a cap or head j'', and this cap j'' has a downwardly 100 extending pin R, designed to fit within a hole i' when the pawl is turned so as to engage

the ratchet, but which rests upon the outer surface of the rocker when not intended to engage the ratchet and holds the pawl *j* away from the ratchet, as shown in Fig. 3. The coil-spring *i* holds the pawl *j* in engagement with the ratchet when not otherwise prevented. The ring *k* has a projecting rim *k'*, which is milled for ease in turning it, and it is loosely supported in the bracket *l*, which embraces it at one end and has its other end secured in any convenient manner to the rail *F*. The ends of the sleeve *k'* are chamfered off, so as to permit the pawl *j* to easily ride from the ratchet to the sleeve. It is readily seen by a glance at Fig. 4 that by reversing the position of the pawl *j* the ratchet may be caused to turn in either direction, thus causing the feed to be in either direction. Now suppose that the whole movement or throw of the rocker *i* causes too rapid a feed and that we wish to diminish the feed. We simply turn the milled head *k'* so that the pawl *j* in rocking back to take hold again will ride up on the sleeve *k'*. Then when it rocks forward again it will not engage the teeth of the ratchet until it passes the end of the sleeve *k'*, or until part of its forward motion has been completed. It will be readily seen that in this way the feed may be regulated anywhere from the full movement of the pawl *j* to nothing at all, because if the sleeve *k'* is turned far enough the pawl *j* will be in contact with the sleeve *k'* for the full length of its motion and will not engage the teeth of the ratchet at all. The feed may be varied in the same way when the pawl is turned in the opposite direction.

In doing heavy work it is sometimes necessary to support the table *E*, and for this purpose we provide a base *u*, which is secured to the bed of the machine. This base *u* is threaded on its inside to receive the screw *t*, and it is split near its top and provided with ears *x*, through which passes the bolt *x'* for clamping the screw *t*, so as to prevent its turning. A block *w* fits loosely in a socket in the head of the screw *t* and is provided with a roller *v*, designed to bear against the under side of the table *E*. The table *E* may be provided with a bearing-surface or strip *E'*, upon which the roller *v* may travel. When a heavy piece of work is to be put on the table *E*, the screw *t* is run up in any convenient manner until the roller *v* is in contact with the bearing-surface *E'*, and then the nut *x''* on the bolt *x'* is tightened, so as to prevent any rotation of the screw and consequent lowering of the support.

To increase the number of available gears for operating the ram *B*, we provide the following mechanism: *I* is the main driving-shaft, upon which is mounted the driving-cone *H*. A gear-wheel *m* is loosely mounted on the shaft *I* and is provided with a flange *m'*. A gear-wheel *n* is slidingly keyed to the shaft *I*, so that it may be moved in either direction along the shaft *I*. The gear-wheel *n*

has a collar *n'*, which is grooved so as to receive the block *s*. Said collar has a flange *n''*. The flange *n''* has openings into which fit *7c* tongues projecting from the flange *m'*. This arrangement simply constitutes a clutching device and may be replaced by any other clutching mechanism. Fulcrumed on a plate *r*, which is secured to the frame *A* of the machine, is the lever *q*, carrying the handle *q'* at its outer end and being pivoted at its forward end at *q''* to the block *s*, so that the gear-wheel *n* may be moved along the shaft *I* in either direction by moving the lever *q*. *75* A second shaft *J* is provided, to which are keyed the gears *o* and *p*, *o* being designed to mesh with the gear *n* when it is in proper position and *p* meshing with the loose gear *m* and with the main driving-gear wheel *G*, which *80* operates the driving-arm *C* in the usual manner. When the lever *q* is in the position shown in the drawings, with the clutching-flanges *m'* *n''* in contact, the gear *m* is caused to rotate with the shaft *I* and turns the gear *p* and through it the gear *G*. Now suppose it is wished to decrease very much the speed of the arm *C*. The lever *q* is shifted until the gear *n* meshes with the gear *o*, at the same time releasing its clutch with the gear *m*. *85* Now the gear *n* turns the gear *o* on the shaft *J*, which causes the gear *p* to rotate, and thus rotates the gear *G*. Of course the gear *m* turns also, but being loosely mounted on the shaft *I* its turning has no effect. As is readily seen, this shifting device for multiplying the speed, in connection with the driving-cone, gives a great variety of speeds at which the arm *C* may be operative. *90*

Having thus described our invention, what we desire to claim as new and to cover by Letters Patent is—

1. In a shaping-machine for operating the ram, an arm pivoted at the lower end and having prongs at the upper end, slots in said prongs, rollers to travel within said slots, a pin upon which are mounted said rollers, said pin being attached to the ram, substantially as and for the purpose described. *105*

2. In a shaping-machine for operating the ram, an arm pivoted in the frame of the machine at the lower end and having prongs at the upper end, slots in said prongs, an adjustable block in the ram, a pin secured to said block, and rollers mounted on said pin and designed to travel on the face of said slot, substantially as described. *110*

3. In a shaping-machine, as a means of regulating the advance of the feed-screw, a rocker loosely mounted on said feed-screw, a pawl carried by said rocker, a ratchet-wheel keyed to said feed-screw, a sleeve loosely mounted on said ratchet, and covering the teeth of said ratchet, a gap in said sleeve which leaves some of the teeth of said ratchet uncovered, and means for varying the angular position of said sleeve with reference to said pawl, substantially as shown and described. *125*

4. In a shaping-machine, the feed-screw *g*,

the rocker *i*, the reversible pawl *j*, the ratchet *h*, the sleeve *k'*, having the milled flange *k''*, and the supporting-bracket *l*, substantially as described.

5 5. In a shaping-machine, a main driving-shaft *I*, a gear *m*, loosely mounted thereon, a gear *n*, slidingly keyed thereto, a clutching device by means of which the gear *m*, may be caused to be rotated by the gear *n*, a second shaft *J*, the gears *p* and *o*, keyed thereto, the gear *G*, for operating the oscillating arm *C*, means for releasing the gear *n*, from its connection with the gear *m*, and for meshing the

gear *n*, with the gear *o*, in combination with the arm *C*, pivoted at its lower end and operated by the gear *G*, said arm having prongs at its upper end, provided with slots, rollers to travel within said slots, a pin upon which are mounted said rollers, said pin being adjustably attached to the ram, substantially as and for the purpose described. 15
